Woodsburgh, N.Y. 11598

Filed Mar. 19, 1968, Ser. No. 11,035

Term of patent 14 years

Int. Cl. D12—14

U.S. Cl. D90—16

FIGURE 1 is a side elevational view of a combination seat support and back rest for bicycle, showing my new design.

FIGURE 2 is a top plan view thereof.

FIGURE 3 is a fragmentary elevational view of the side opposite that shown in FIGURE 1.

FIGURE 4 is a fragmentary rear elevational view thereof.

FIGURE 5 is a fragmentary front elevational view thereof.

FIGURE 6 is a fragmentary side elevational view of a modified form of the combination seat support and back rest shown in FIGURE 1.

The bicycle and seat, fragmentarily shown in broken lines, are included only for illustrative purposes.

I claim:

The ornamental design for a combination seat support and back rest for bicycle, as shown and described.
